UNITED STATES PATENT OFFICE.

ARNOLD KLINGER, OF CHICAGO, ILLINOIS.

SPRAYING DEVICE.

No. 923,277.

Specification of Letters Patent.

Patented June 1, 1909.

Application filed October 2, 1908. Serial No. 455,810.

To all whom it may concern:

Be it known that I, ARNOLD KLINGER, a subject of the King of Hungary, residing at Chicago, in the county of Cook and State of Illinois, have invented certain new and useful Improvements in Spraying Devices, of which the following is a specification.

This invention relates to improvements in spraying devices and more particularly to a spraying device of that class in which compressed air is employed to expel the spraying material.

The object of the invention is to provide a simple and economically constructed spraying device which is equally as well adapted for spraying powders as for spraying liquids and in which the spray is controlled by a simple valve, such as a push valve.

A further object of the invention is to provide a spraying device having a discharge chamber opening from near the bottom of the receptacle and in which the spraying material is confined by air pressure from beneath in position to be ejected from the nozzle when the outlet from the chamber is opened.

The invention consists of the matters hereinafter described in the specification and more fully pointed out and defined in the appended claims.

In the drawings—Figure 1 is a central vertical section of a device embodying my invention. Fig. 2 is a transverse section thereof. Fig. 3 is a vertical section of the air pump. Fig. 4 is a section taken on line $y-y$ of Fig. 3. Fig. 5 is a view partly in section and partly in side elevation of the nozzle or spraying tip. Fig. 6 is an enlarged, fragmentary section of one form of the discharge pipe. Fig. 7 is an enlarged, fragmentary section of the discharge pipe shown in Fig. 1. Fig. 8 is an enlarged, fragmentary, vertical section of the air pump.

As shown in said drawings, A indicates a receptacle of any preferred size and construction which is provided with a top a and a bottom a' , the latter of which is concaved or dished on its under side and is provided with a filling aperture in which is removably engaged a plug a^2 .

Rigidly supported within said receptacle is the air pump B, the barrel b of which extends from near the bottom of the receptacle upwardly through the top a and is provided with a top or cover b' having an axial aperture therethrough. Within said barrel, near

the lower end thereof, is a centrally apertured valve seat b^2 , and beneath said seat is a valve closure b^3 having a valve stem b^4 thereon which extends downwardly through the bottom b^5 of the barrel. A spring b^6 engages at one end against the bottom b^5 and at the other end against the valve closure b^3 and acts to normally hold the closure against said seat. Said closure is provided near its periphery with apertures b^7 and the bottom b^5 is provided with apertures b^8 through which air may pass from the pump to the receptacle.

Slidably engaged in the top b' of said barrel is a rod b^9 on the lower end of which is an inverted cup-shaped plunger b^{10} , adapted when the rod is forced downwardly to fit closely to the sides of the barrel and force the air beneath the same into the receptacle where it is confined by the valve closure b^3 . When said plunger is raised, the edges thereof collapse and permit the air in the upper part of the barrel to pass beneath it.

The receptacle A is provided with a handle a^3 on one side thereof, and rigidly engaged within the receptacle, adjacent the handle, is the discharge chamber C, which may be of any preferred construction, but which, as shown, is cylindrical and the lower end of which opens in close proximity to the bottom a' of the receptacle. In the upper end of said chamber is a valve casing c which protrudes from the top of the receptacle. A valve stem c' extends downwardly through said valve casing and is provided with a valve closure c^2 on its lower end adapted to seat against the bottom of the casing and close the passage therethrough. The upper end of said stem c' is provided with a head c^3 and between the head and the top of the casing is a spring c^4 adapted to normally hold the closure c^2 seated.

A discharge pipe D is rigidly engaged on the top of the receptacle and opens at one end from said valve casing c. The opposite end d of said pipe is provided with a peripheral groove d' and tapers from said groove to the extremity, as shown more clearly in Figs. 6 and 7. Connected on said tapered end is the pipe extension D', which is slotted in one end to enable it to be sprung onto said end d , and is provided on its other end with a top D^2 having longitudinal slots D^2 therein for the escape of the spraying material. Said extension is preferably curved, as shown in Fig. 1, to facilitate its use. By turn-

ing the extension, the liquid may be sprayed upwardly, downwardly or to either side at any desired angle, so that all sorts of cracks and crevices may be reached and filled with 5 the liquid.

In the construction shown in Fig. 6, a union D^3 is adapted to be engaged on the pipe end d , as before described with reference to the pipe D' , and is roughened to permit 10 the attachment of a rubber hose, if desired.

The operation is as follows: The receptacle is partially filled with the spraying material through the filling aperture in the bottom and air is pumped into the receptacle by 15 means of the pump B until a sufficient pressure is obtained to eject the spraying material. The air, of course, will rise above the spraying material in the receptacle, and, when the valve c^2 is operated, the discharge 20 chamber C will be filled and the material will be ejected through the discharge pipe. When the valve c^2 is released, the pipe D is closed, but the discharge chamber will remain filled owing to the air pressure above 25 the material in the receptacle.

Owing to the close proximity of the discharge chamber to the handle a^3 , the valve c^2 may be operated by the thumb of the hand holding the receptacle. Obviously a spraying 30 device constructed in accordance with my invention is adapted to provide a good spray and many details of form and construction may be varied without departing from the principles of my invention.

35 I claim:

1. In a spraying device, the combination of a cylindrical receptacle closed at the top and having a dished bottom provided with a filling opening, a plug to close the same, a 40 handle on the side of the receptacle, an air pump extending into the receptacle from the top, a vertical discharge chamber within said

receptacle, lying along the side of the same adjacent the handle, a valve casing in the upper end of the discharge chamber, a valve-piece which closes the opening into said valve chamber, a stem for said valve-piece provided with a thumb piece in position to be depressed by the thumb of the hand which holds the handle, a discharge pipe leading 45 from the valve casing and extending across the top of the receptacle, a curved extension pipe swiveled on the end of said discharge pipe, and a nozzle on said extension pipe, substantially as described. 55

2. In a spraying device, the combination of a cylindrical receptacle, a handle on the side of said receptacle near the top, an air pump extending into the receptacle from the top, a vertical discharge chamber within said 60 receptacle lying along the side of the same adjacent to the handle, a valve casing in the upper end of the discharge chamber, a valve-piece which closes the opening into said valve chamber, a stem for said valve-piece provided with a thumb piece in position to be depressed by the thumb of the hand which holds the handle, a discharge pipe leading 65 from the valve casing and extending across and projecting from the top of the receptacle, the end of said discharge pipe being tapered and provided with a peripheral groove, a curved extension pipe constructed so as to be sprung over the tapered end of said discharge pipe and provided with a rib which engages 70 with the groove on the discharge pipe, and a pointed nozzle on the end of said curved extension, provided with longitudinal slots for 75 the escape of the spraying material. 75

ARNOLD KLINGER.
